UNITED STATES PATENT OFFICE

96,980

DESIGN FOR A PIANO CASE

Carl L. Haddorff, Rockford, Ill.

Application August 1, 1935, Serial No. 57,905

Term of patent 14 years

To all whom it may concern:

Be it known that I, Carl L. Haddorff, a citizen of the United States, residing at Rockford, in the county of Winnebago and State of Illinois, have invented a new, original, and ornamental Design for a Piano Case, of which the following is a specification, reference being had to the accompanying drawing, forming part thereof.

In the drawing:

Fig. 1 is a perspective view of a piano case, the

dominant feature of which is shown in solid lines and comprises a lower vertical portion having a bulging front.

Fig. 2 is an end view of the case shown in Fig. 1.

Fig. 3 is a bottom view of the case shown in Fig. 1.

I claim:

The ornamental design for a piano case, as shown and described.

CARL L. HADDORFF.
